ENGINE STARTER

Edward M. Claytor, Anderson, Ind., assignor to
 General Motors Corporation, Detroit, Mich., a
 corporation of Delaware

Application March 7, 1938, Serial No. 194,282

14 Claims. (Cl. 290—37)

This invention relates to engine starting apparatus and more particularly to the engine starting apparatus in which a pinion driven by the starting motor is shifted by pedal operation into engagement with the flywheel gear of the engine to be started, the pedal operation effecting also the closing of the starting motor switch. In order to prevent driving the starting motor by the engine at an excessive rate of speed and before the pinion is disconnected from the engine after the starting operation, pedal shift engine starting apparatuses include an overrunning clutch between the pinion and the armature shaft of the starting motor. While the manufacturer of engine starting apparatus aims to provide an overrunning clutch which will always overrun under all conditions, it occasionally happens that the overrunning clutch does not function, and the result is that the motor armature shaft is overspeded before the driver can remove his foot from the operating pedal. If the clutch fails to function for an appreciable length of time, the overspeeding of the motor armature will cause its windings to be dislodged due to centrifugal force.

It is an object of the present invention to provide for the control of the engine starting motor in such a way that the pinion will be withdrawn automatically from the engine flywheel gear regardless of whether the driver continues to apply pressure to the foot pedal which controls the starter. To accomplish this object I provide, in the mechanical connection between the operating foot pedal and the lever on the starting motor which shifts the pinion and closes the switch, an electromagnetically operated latch of novel construction differing from similar devices found in the prior art, in that the operation of the latch is independent of the force applied by the car driver to the starter pedal. In the magnetic latches of the prior art the latch members are so constructed and arranged that the forces applied between them, when the driver keeps his foot on the starter pedal, are such as to hinder the unlatching, due to friction set up between the engaging surfaces of the latch members. In the disclosed embodiment of my invention, I so relate these latch parts that the force applied by the driver upon the foot pedal is transmitted in such a way as to tend to unlatch the latch members rather than to set up a frictional force which tends to keep them latched up, regardless of the deenergization of the latch operating magnet.

Further objects and advantages of the present

invention will be apparent from the following description, reference being had to the accompanying drawings wherein a preferred embodiment of the present invention is clearly shown.

In the drawings:

Fig. 1 is a fragmentary side elevation partly in longitudinal section of an engine starting motor control device embodying the present invention.

Fig. 2 is a sectional view in the line 2—2 of Fig. 1.

Fig. 3 is a fragmentary view partly in section, the section being taken on the lines 3—3 of Fig. 1.

Fig. 4 is a wiring diagram of a control circuit embodying the mechanism shown in Figs. 1, 2 and 3; and

Fig. 5 is a wiring diagram showing a modified form of the invention.

Referring to the drawings, 20 designates the field frame of an electric motor having an armature 21, mounted on a shaft 22 journaled in a bearing at the left hand of the field frame 20 not shown. Shaft 22 is journaled in a bearing 23 carried by a gear housing 24 attached to frame 20. The shaft 22 has a splined portion 25 drivingly connected with a sleeve 26 integral with a driving clutch member or cam 27 of an overrunning clutch comprising also rollers 28 and an outer shell or driven member 29 attached to a pinion 30 carrying a plain bearing 31 which is slidably along a plain cylindrical portion 32 of the shaft 22. A stop ring 33 limits movement of the pinion 30 toward the right into mesh with the flywheel gear 34 (of the engine to be started). A sleeve 35 mounted on the armature shaft 22 limits movement of the pinion shifting sleeve 26 toward the left. A shifting collar, made of flanged members 36 and 37 welded together, slides along the outer cylindrical surface of the sleeve 26 and is retained by a wire split ring 38 received by a groove in the end of sleeve 26. A spring 39 is located between the shifting collar 36, 37 and a shoulder on the sleeve 26, and serves to transmit motion from the shifting collar to the sleeve 26.

The shifting collar 36, 37 receives studs 40 carried by the arms 41 of a bifurcated lever comprising two sections 42 secured to a hub 43 pivoted on a screw 44 which is screwed or press-fitted into a lug 45 integral with the gear housing 24. A flanged washer 46 surrounding the screw 45 serves to retain a coiled spring 47 which is retained in an initial state of torsion, one end 48 being received by a lug 49 on the frame 24 and the other end 50 being biased in a clockwise direction against a stud 51 attached to lever parts 55

42. The lever parts 42 provide an arcuate projection 52 adapted to engage switch plunger 53, which closes switch contacts contained within a switch case 54, mounted upon the motor frame 5 20, as will be explained in detail in connection with the description of Fig. 4.

The screw 44 provides a bearing for a hub 60 of an operating lever 61 retained on the screw 44 by a washer 62 and a nut 63 threaded on the end 10 of the screw 44. The operating lever 60 is connected with the gear shifting lever 42 by an electromagnetically controlled latch comprising a latch pin 65 screwed into the lever 60 and retained by lock washer 66 and lock nut 67, and 15 a latch lever 70 having, integral therewith, spaced ears 71 by which the lever is pivotally mounted on a screw 72 threaded into the lever 42 and retained therein by a lock washer 73 and a lock nut 74. The latch lever 70 is integral also with an 20 armature 75 which cooperates with an electromagnet 76, which comprises a magnetizable cup-shaped shell 77 concentric with respect to a magnetizable core 78 surrounded by an electromagnet winding 79. This structure is attached to a bracket 80 riveted to the lever members 42, 42.

As stated before, the lever 42 is biased into the normal position shown in Fig. 1 by the spring 47. The lever 61 is biased into the position shown in Fig. 1 by a coil spring 68, surrounding the hub 30 60 and having one of its ends fixed to the housing 24, and the other of its ends pressing in a clockwise direction against lever 61.

The latch lever 70 has a notch 81 which is defined by a long shoulder 82 against which the 35 latch pin 65 normally bears. The other side of the notch 81 is defined by a surface 83 which is not parallel to the surface 82, but makes a substantial acute angle, defined by the lines a—b and b—c. Line b—c is a radial line extending 40 from the axis of rotation of lever 61, namely the center of screw 44 and passing through the center of the stop 65. This angle is between 18° and 22°; 20° gives satisfactory results.

The latch lever 70 is urged clockwise, so that 45 the latch pin 65 will bottom in the notch 81, by a spring 90 coiled around the screw 72 and having an end 91 biased counterclockwise against a shoulder 92 provided by lever 42, as shown in Fig. 1, and having an end 93 biased clockwise 50 against that part of the lever 70, which merges into the armature 75, as indicated at 75a in Fig. 1. The spring 90 tends to keep the latch members 70 and 65 normally in cooperative relation.

If the operator causes the lever 61 to be moved 55 counterclockwise, the pin 65 will bear against the latch 70 and will attempt to move the lever 42 in a counterclockwise direction, but such movement cannot take place unless the electromagnet 79 is energized. The reason for this is that, the 60 spring 47 which resists movement of the lever 42 being relatively stiff, the reaction of the surface 83 of lever 70 against the pin 65 becomes so great before the resistance of spring 47 is overcome that the force applied between the surface 83 and the latch pin 65 will become great enough to 65 overcome the force of the spring 90 and the latch lever 70 will separate itself from the latch pin 65, and no motion will be transmitted between the lever 61 and the lever 42. It should be noted that 70 the action line of force between the pin 65 and the lever 80 will be at right angles to the line a—b and will pass through the center of the pin 65. This force line will, therefore, react in a direction tending always to move the latch lever 75 70 in a counterclockwise direction against resist-

ance offered by the spring 90. The spring 90 is only a light spring tending to keep the latch members in engagement, but it alone is ineffective to retain the members in engagement unless the spring 90 is aided by the energized electromagnet 79, which urges the armature 75 in a clockwise direction. As will be explained in connection with Fig. 4, the electromagnet 76 is connected in the starter circuit in such a way that, during the starting operation, it will be energized, but when the engine becomes self-operative it will be deenergized. One of the features of the invention is the spring 90 which tends to keep the latch parts in engagement, and which tends also to keep the latch armature 75 relatively close to the magnet 76 so that the air gap is relatively small. Therefore, a much smaller electromagnet can be used to retain the armature in the latch making position, as compared with the conventional type of magnetic latch where the gap between the magnet and latch armature is relatively great.

Referring now to Fig. 4, which shows how the latch magnet is connected with the starting and generating circuit, the operating pedal is indicated by numeral 100 and is connected by a rod 101 with the lever 61. The switch plunger 53 which is retained in contact open position by a spring 53a carries a bridging contact 102, engageable with stationary contacts 103 and 104. Contact 104 is connected with the circuits of the electric motor which operates the armature shaft 22. The contact 103 is connected by a wire 106 with a battery 107 grounded at 108. The battery is charged by a generator 109 grounded at 110 and connected with the battery by reverse current relay 111.

Relay 111 comprises an electromagnetic core 112 surrounded by a voltage coil 113 grounded at 114 and by a current or series coil 115 connected with a generator by wire 116 and with the hinge of the armature 117. The armature 117 carries a contact 118 which is engageable with the contact 119 connected by wire 120 and wire 106 with the battery 107. The armature 117 insulatingly supports a contact 121 engageable with a stationary contact 122. The movable contact 121 is grounded at 123. A spring 124 normally maintains the armature in the position shown in Fig. 4. The contact 122 is connected by wire 125 with one end of the latch magnet coil 79, the other end being connected by wire 126 with a stationary contact 127 associated with the ignition switch 128. Switch 128 includes contacts 129 and 130, which are bridged together with contact 127 by three-blade bridging contact 131. Contact 130 is connected by wire 132 with wire 120. Contact 129 is connected with the engine ignition apparatus.

To start the engine, the operator closes the 60 ignition switch 128, thereby connecting the latch magnet coil 79 with the battery 107 through the following circuit: battery 107, wire 106, wire 120, wire 132, contact 130, contact 131, contact 127, wire 126, coil 79, wire 125, contact 122, contact 121, ground 123 and ground 108. The latch magnet 79 is now energized and the latch members 65 and 70 will be retained in engagement during the engine starting operation. The car driver then presses the starter pedal 100, thereby causing the lever 61 to move counterclockwise, thereby transmitting pressure between the latch pin 65 and the latch lever surface 83, thereby causing the gear shift lever 42 to rotate counterclockwise against the resistance of spring 47. The tend- 75

ency of the forces exerted between the latch pin 65 and the latch lever surfaces 83 is such as to cause separation of the latch members, but this tendency is resisted by the energized electromagnet 79. Therefore, when this magnet is energized, motion will be transmitted from the pedal 100 to the shifting lever 42 to cause the pinion 33 to be moved into engagement with the engine flywheel gear 34 and the contacts of the starter switch to be closed by the engagement of surface 52 of lever 42 with switch operating plunger 53. In case of abutment of the ends of the teeth of pinion 33 with the ends of the teeth flywheel gear 34 before meshing, motion of the lever 42 is not arrested, because motion is transmitted from the lever 42 to the pinion 30 through the shifting spring 39 which becomes compressed beyond its initial stage of compression and permits closing of the starter switch by the lever 42, whereupon the motor 105 will rotate the pinion 30, thereby bringing it to meshing registration with the gear 34, whereupon the abnormally compressed spring 39 will be released quickly to snap or jump the pinion 30 into mesh with the flywheel gear 34, whereupon the engine will be started in the usual manner by rotating its crank shaft.

When the engine becomes self-operative, and has attained a predetermined speed, such that the voltage of the generator 109 attains a certain value, the relay 111 will be energized by its voltage coil 113 sufficiently to cause the armature 117 to be attracted toward the core 112, thereby closing the contacts 118 and 119 to complete the battery charging circuit, and thereby opening the contacts 121 and 122 to interrupt the circuit of the latch magnet coil 79. Immediately the flux lines of the latch magnet diminish and the light spring 90 becomes less and less able to hold the latch parts in engagement. Therefore, as the flux lines die away between the armature 75 and the core 73 and shell 77 of the latch magnet 76, the force of application between the latch lever surface 83 and the latch pin 65 becomes effective to cause counterclockwise rotation of the latch lever 10, thereby interrupting the mechanical connection between the pinion shifting 42 and the pedal operated lever 61, thereby permitting the spring 59 to withdraw the pinion 30 from engagement of the flywheel gear 34, regardless of whether the driver consciously or unconsciously fails to remove his foot from the pedal 100 the instant the engine starts.

The present invention provides for the automatic disconnection of the pinion shifting lever from the mechanism directly operated upon by the driver's foot. Consequently the starter pinion is not maintained in mesh with the engine flywheel gear a moment longer than necessary for the starting operation. The instant the engine becomes self-operative and comes up to speed, the starter pinion is demeshed from the engine gear automatically since the clutch magnet is automatically deenergized and permits the spring 47 to perform its function regardless of whether the driver has released foot pressure on the pedal 100.

During that brief interval of time between the actual beginning of self-operation of the engine and the time when the cut-out relay closes, the engine will be spurting ahead of the starting motor, so that the overrunning clutch will begin to function to prevent the driving of the motor by the engine, but that brief interval is materially shortened due to the fact that demeshing of gears takes place automatically immediately following

the closing of the cut-out relay. Therefore, should the overrunning clutch fail to overrun for any reason, it will not be a serious matter, because the latch magnet will become deenergized before the engine speed can attain a value which would be dangerous to the starting motor, should the engine continue to drive it.

In the modified form shown in Fig. 5, the latch magnet 79 is not grounded through an extra set of contacts on the cut-out relay. Instead of the modified cut-out relay 111 shown in Fig. 4, I use the conventional cut-out relay represented by the rectangle 111a. In this circuit the latch magnet 79 is connected with the generator third brush 109a and gets its ground circuit either through the armature 109b or through the field winding 109c. If the brush contact is satisfactory, the circuit of lowest resistance will be directly through the armature; but it may be through the field circuit 109 if that is the path of least resistance. Obviously, the circuit through field 109 will give a voltage drop in the line thus requiring more ampere turns in the winding 79 in order to give sufficient energization. However, the arrangement shown in Fig. 5 is simpler, since the extra set of contacts on the cut-out relay is avoided. Obviously the deenergization of the magnet 79 results from opposing the battery C. E. M. F. with generator voltage. While the engine is running the starter cannot be operated. The pedal 100, therefore, can be used to operate other controls of the engine, such as the throttle valve.

While the embodiment of the present invention as herein disclosed, constitutes a preferred form, it is to be understood that other forms might be adopted, all coming within the scope of the claims which follow.

What is claimed is as follows:

1. A starter for internal combustion engines comprising an electric motor, a current source, a mechanism for connecting the motor with the engine to be started and including an overrunning clutch driven by the motor and a pinion driven by the clutch and movable into mesh with the flywheel gear of the engine to be started, a pinion shifting member for meshing the pinion, a spring for demeshing the pinion, a starter switch actuated by said member, a pedal operated member, disconnectable means connecting said pedal member and pinion shifting member and comprising normally connected latch parts carried respectively by said members, said latch parts being so related that pressure exerted between them tends to unlatch them, an electromagnet effective to hold the latch parts in engagement during the engine starting operation, and means responsive to self-operation of the engine for rendering the electromagnet inoperative whereby the means connecting the members becomes disconnected due to pressure exerted between the latch members and the spring is released to demesh the pinion regardless of failure to release the pedal operated member.

2. An engine starter according to claim 1 in which means responsive to the voltage of a generator driven by the engine renders the electromagnet inoperative to hold the latch members in connected relation.

3. An engine starter according to claim 1 in which the armature of the electromagnet is normally at the minimum distance from the pole faces of the electromagnet.

4. An engine starter according to claim 1 in which one of the latch parts is a pivoted lever connected with the armature of the electromagnet.

net, and in which a light spring is used to maintain the latch parts normally connected and the armature normally close to the magnet pole faces.

5. An engine starter according to claim 1 in which the pedal operated member and the pinion shifting members are coaxially pivoted levers, in which the latch parts comprise a pin carried by one of the levers and a pivoted latch plate carried by the other lever, and in which the electromagnet includes an armature attached to the pivoted latch plate.

6. An engine starter according to claim 1 in which the pedal operated member and the pinion shifting members are coaxially pivoted levers, in 15 which the latch parts comprise a pin carried by the pedal lever and a pivoted latch plate carried by the pinion shifting lever, and in which the electromagnet core is carried by the pinion shifting lever and the electromagnet armature is integrated with the latch plate.

7. An engine starter according to claim 1 in which the pedal operated member and the pinion shifting members are coaxially pivoted levers, in which the latch parts comprise a pin carried by 25 the pedal lever and a pivoted latch plate carried by the pinion shifting lever, the latch pin bearing, during pinion shifting into mesh with the engine flywheel gear, against a surface of the latch plate which is inclined at an angle of between 18° and 30 22° with respect to a line intersecting the center of the latch pin and the axes of the coaxially pivoted levers.

8. A starter for internal combustion engines comprising a starting motor, a movable control member for causing the motor to operate, a spring for returning the motor control member to non-operating position, a pedal operated member for actuating the movable member, disconnectible means connecting said members and comprising 35 40 normally connected latch parts carried respectively by said members, said latch parts being so related that pressure exerted between them, due to the resistance of said spring, tends to unlatch them, an electromagnet effective to hold the latch parts in engagement against the resistance of said spring during the engine starting operation, means responsive to self operation of the engine for rendering the electromagnet inoperative whereby the latch parts become disconnected 45 50 due to the resistance of said spring which, on be-

ing released, returns the motor control member to non-operating position regardless of the status of the pedal operated member, and whereby the pedal operated member is inoperative to control the starting motor while the engine is running.

5

9. An engine starter according to claim 8 in which means responsive to the voltage of a generator driven by the engine renders the electromagnet inoperative to hold the latch members in connected relation.

10

10. An engine starter according to claim 8 in which the armature of the electromagnet is normally at the minimum distance from the pole faces of the electromagnet.

10

11. An engine starter according to claim 8 in which one of the latch parts is a pivoted lever connected with the armature of the electromagnet, and in which a light spring is used to maintain the latch parts normally connected and the armature normally close to the magnet pole faces.

20

12. An engine starter according to claim 8 in which the pedal operated member and the motor control members are coaxially pivoted levers, in which the latch parts comprise a pin carried by one of the levers and a pivoted latch plate carried by the other lever, and in which the electromagnet includes an armature attached to the pivoted latch plate.

25

13. An engine starter according to claim 8 in which the pedal operated member and the motor control members are coaxially pivoted levers, in which the latch parts comprise a pin carried by the pedal lever and a pivoted latch plate carried by the motor control lever, and in which the electromagnet core is carried by the motor control lever and the electromagnet armature is integral with the latch plate.

30

14. An engine starter according to claim 8 in which the pedal operated member and the motor control members are coaxially pivoted levers, in which the latch parts comprise a pin carried by the pedal lever and a pivoted latch plate carried by the motor control lever, the latch pin bearing, during starting motor operation, against a surface of the latch plate which is inclined at an angle of between 18° and 22° with respect to a line intersecting the center of the latch pin and the axes of the coaxially pivoted levers.
